Res. 554

Samuel H. Sailor, of Philadelphia, Pa.

Assignor to

Charles W. Warnick & Fredk Leibrandt, of Philadelphia aforesaid,
Letters Patent No. 554. Dated Apr. 19th 1853.

.....

The schedule referred to in these Letters Patent and making part of the same

.....

To all whom it may concern:

Be it known, that I, Samuel H. Sailor, of the City & County of Philadelphia, and State of Pennsylvania, have invented or produced a new and original design in cook stoves called

"Victor Complete,"

and I do hereby declare that the following is a full, clear, and exact description of the same; reference being had to the annexed drawings forming part of this specification, in which

Figure 1. is a side elevation of the stove-

Figure 2. a front elevation of the same

Figure 3. a rear elevation.

In the several figures, ornaments which are symmetrical, have but one half, the design shown.

Similar letters in the several figures, refer to the same part of the stove.

The upper front plate A, is surrounded by a bead a, elevated above the surface of the plate, and on the ends outside of the bead a, are the mouldings b; the surface enclosed by the bead a, is ornamented in bas-relief by the wreath c, having the branches d, bearing the leaves e, and flowers f, sweeping gracefully from its lower portion towards the ends of the plate. Above the ornament is the inscription "Victor Complete" in raised capitals, and below "Design patented 1853," in raised capitals and numerals; the ornaments, mouldings and inscriptions having the configuration and arrangement shown in figure 2.

The feed door B, is surrounded by the moulding g, forming a sunken panel, upon which are the branches h, leaves i, and flowers j, having the configuration and forming the ornamental design in bas-relief seen in figure 2.

The lower front doors C, are raised above the surface of the plate D, by the ovoli k, and cavetto l, and the panel surrounded by the bead m. The panels are ornamented in bas-relief by the branches n, leaves o, and flowers p, arranged as shown in figure 2. Upon the lower front plate D, and exterior to the doors C, are the flowers q, and foliage r; each group enclosed by the moulding s, and arranged as set forth in figure 2. Between the front plate D, and the extremities of the raised feed passage are the curved surfaces t, each ornamented by the flower u, in bas-reliefs.

Upon each side of the stove is an oven door, F, raised above the surface of the plate by the cavetto u, and ovoli v, with the panel enclosed by the bead w; this panel bears the wreath x, branches y, and flowers z, in bas-relief, having the configuration and arrangement, and forming the ornamental design set forth in figure 1. Upon the panel above the wreath x, is the inscription "Victor" in raised capitals. Besides the oven doors F, each side plate has a raised panel G, surrounded by a moulding H, similar to that around the doors F, and bearing upon its surface foliage, flowers, and branches forming the ornamental design in bas-relief, represented by I, figure 1; one of the panels is movable forming a feed door.

The front feet K, are of the form shown in figures 182, and are ornamented in bas-relief by the flowers a', leaves b', and sweeps c', terminating

3

Des. 554

in the scrolls d', arranged as fully shown in the drawing. The surface of the upper part of the rear leg I, is sunken and ornamented by the scrolls e', and scales f; below which is the flower h', connecting this upper portion of the leg with the swags i' terminating in the scrolls k', like those on the foot K; the leg having the form, and ornaments the arrangement seen in figures 1. and 3.

What I claim as my invention or production, and desire to secure by Letters Patent, is

The configuration and arrangement of the ornaments in bas-relief as described in this specification and annexed drawings, on the front plates A, and D, feed door B, curved surface E, doors C, and F, panels G, and legs K, and I, forming a new and original design of cook stove, denominated the "Victor Complete."

In testimony whereof, I have hereunto signed my name before two subscribing witnesses.
